WINDOW FRAME STRUCTURE

Richard N. Anderson, Owensboro, Ky., assignor to V. E. Anderson Mfg. Co., Owensboro, Ky., a corporation of Kentucky

Filed Oct. 16, 1967, Ser. No. 9,009

Term of patent 14 years

(Cl. D13—1)

FIGURE 1 is a perspective view of a window frame structure showing my new design.

FIGURE 2 is an enlarged transverse cross section view of my window frame structure taken substantially on the line 2—2 in FIGURE 1.

FIGURE 3 is an enlarged transverse cross section view of my window frame structure similar to the section view of FIGURE 2 and showing an alternative head and jamb extrusion.

FIGURE 4 is an enlarged transverse section view of my window frame structure taken substantially on the line 4—4 in FIGURE 1.

FIGURE 5 is an enlarged perspective view of the outside of the lower right hand corner of the window frame structure illustrated in FIGURE 1.

FIGURE 6 is an enlarged partial perspective view of the inside of the lower right hand corner of the window frame structure illustrated in FIGURE 1.

The head and jamb members of my window frame structure are identical in cross section.

The lower left hand corner of my window frame structure is a mirror image of the lower right hand corner of my window frame structure.

The head and jamb members of my window frame structure are mitered at forty-five degrees and connected to form the upper corners of my window frame structure.

I claim:

The ornamental design for a window frame structure, substantially as shown and described.
